ROCK DRILL

John C. Curtis and Elmer G. Gartin, Claremont,
N. H., assignors to Sullivan Machinery Company,
a corporation of Massachusetts

Application June 25, 1940, Serial No. 342,327

17 Claims. (Cl. 255—45)

This invention relates to rock drills and more particularly to improved guiding and feeding means for a rock drill hammer motor of the mounted drifter type.

It is an object of this invention to provide an improved rock drilling apparatus. It is another object of this invention to provide an improved supporting, guiding and feeding means for a rock drill hammer motor of the mounted type. It is still another object of this invention to provide an improved feed screw and nut arrangement supported for operative engagement with a drill hammer motor in an improved manner. Still another object of this invention is to provide an improved structure for supporting and guiding a drill hammer motor relative to the work and having associated therewith motor feeding means supported and shielded by said structure from damaging blows. Yet a further object of the invention is to provide an improved drifter-type drilling apparatus having improved operative connection between the hammer motor and the feeding means therefor. These and other objects and advantages of the invention will hereinafter more fully appear.

In the accompanying drawings, in which for purposes of illustration one form and a modification of the invention have been shown.

Fig. 1 is a side elevational view of a rock drilling apparatus having embodied therein one form of the invention.

Fig. 2 is a plan view of the rock drilling apparatus shown in Fig. 1.

Fig. 3 is a rear end elevational view of the rock drilling apparatus shown in Fig. 1.

Fig. 4 is a front end elevational view of the rock drilling apparatus shown in Fig. 1.

Fig. 5 is a fragmentary vertical sectional view taken on the plane of the line 5—5 of Figs. 1 and 7.

Fig. 6 is a longitudinal vertical sectional view taken on the plane of the line 6—6 of Fig. 5 and showing the feed nut and a portion of the feed screw.

Fig. 7 is a horizontal sectional view taken on the plane of the line 7—7 of Fig. 5 and showing the rear portion of the improved guiding and feeding means for the drill hammer motor.

Fig. 8 is a plan view with parts broken away, of the forward portion of the improved guiding and feeding means.

Fig. 9 is a vertical sectional view taken on the plane of the line 9—9 of Fig. 8.

Fig. 10 is a vertical transverse sectional view taken on the line 10—10 of Fig. 7.

Fig. 11 is a vertical sectional view like that of Fig. 6 but showing a modified form of connection between the feed nut and the drill motor.

Fig. 12 is a vertical sectional view taken on line 5 12—12 of Fig. 11.

In the illustrative form of the invention shown in Figs. 1 to 10 inclusive, a hammer motor, generally designated 1, is mounted upon an improved supporting and guiding means 2 and is operatively connected in an improved manner to feeding means 3, as shown in Fig. 6.

The hammer motor is shown as of the usual reciprocating hammer piston type and includes a cylinder 5 having a front chuck housing 6 containing a chuck (not shown) for receiving the shank of a drill steel 7. At the rear end of the cylinder is a head block 8 having connected thereto a supply line 9 for supplying pressure fluid to the motor cylinder. The chuck housing 6 and the rear head block 8 may be secured to the motor cylinder in any suitable manner and are shown here as being held in assembled relation by side rods 11. At the sides of the motor cylinder are boss-like projections 12 having aligned openings for receiving sleeve members 14 in positions extending parallel to the longitudinal axis of the hammer motor. Guide rods 16, later referred to in more detail, have a sliding fit within the sleeve shaped members 14 and form part 30 of the supporting and guiding means 2 for the hammer motor.

Referring to the improved supporting and guiding means 2, it will be noted that there is provided a swivel plate 18 adapted for mounting in the clamp of a conventional saddle mounting, and formed integral with the swivel plate is an elongated body portion 19 providing an arcuate shaped trough 20 within which a generally tubular-shaped member 21 is fixed in any suitable manner, as, for example, by welding, by clamping, by screws, etc. At the forward end of the tubular shaped member is a transversely extending support member 23 having midway between its sides a sleeve portion 24 fitting within the end of 45 the bore in the member 21, as shown in Fig. 9. Formed herein in oppositely extending arm portions of the support member are openings 25 for receiving the forward reduced ends of the guide rods 16. Nuts 26 threaded upon the ends of the 50 guide rods hold the support member and the guide rods firmly together. At the rearward end of the tubular shaped member 21 is a transversely extending support member 28 having a bore 29 midway between its sides for receiving the rearward end of the tubular member, and the support mem-

ber 28 is split at the lower side of the opening 29 and provided with projecting portions 30 carrying a clamping bolt 31 for clamping the support member onto the tubular shaped member 21. At the outermost portions of the support member 28 are openings for receiving the reduced, threaded rear ends of the guide rods 16. Nuts 32 screwed on the threaded rear ends of the guide rods 16 at opposite sides of the support member 28 are provided for adjustably clamping the support member and the guide rods rigidly together. A feed screw 33 extends axially through the tubular member 21 and is rotatably supported at its forward end within a spool shaped member 35 fitting within the bore of the tubular member as shown in Fig. 9. A bolt 36 threaded in an opening 37 through the tubular member 21 projects into a groove 38 in the outer surface of the spool shaped member and holds it against movement longitudinally of the tube. The rearward end of the feed screw is rotatably supported by a projecting portion 40 formed integrally with and extending rearwardly from the support member 28. Attached to the rearward end of the feed screw is a handle 41 providing for manual rotation of the feed screw. Formed in the upper side of the tubular member 21 is an opening 42 extending from the rearward end of the tube to a point spaced a short distance from its forward end. Projecting from the lower sides of the head block 8 and the cylinder 5 are portions 44 and 45 respectively and both of these portions project into the opening 42. The portion 44 includes an annular portion 46 projecting into and herein shown as slidably fitting the bore of the tubular member, and mounted within the annular portion 46 is a feed nut 47 which is in threaded engagement with the feed screw. The rearward end of the feed nut is provided with an enlarged portion 49 for abutting the annular portion 46, and the upper side of the enlarged portion is provided with a flat surface 50 for engaging a flat surface 51 on the portion 44 and holding the feed nut against rotation relative to the hammer motor. The forward end of the feed nut extends beyond the annular portion 46 and has threaded thereon a nut 53 for clamping the feed nut firmly within the annular portion. A flat surface 54 on the portion 45 depending from the cylinder is adapted to engage a flat surface 55 on the nut 53 when the parts are assembled and to prevent the nut 53 from turning and loosening the feed nut from the rear head block. A washer 56 is shown between the nut 53 and the depending portion 44. The support member 28 is provided with an opening 57 within which a cylindrical portion of a key 59 is fixed in any suitable manner, and a portion 60 on the key projects into the bore 29 and fits the elongated opening 42 for locking the tubular member 21 against rotation relative to the hammer motor and precluding distortion thereof by the clamp mechanism 30, 31.

In the modification shown in Figs. 11 and 12, the structure is the same as that described above except that a feed nut 62 fits within the bore of the tubular member 21 and is provided with portions 63 projecting through the opening 42 in the tubular member and fitting within recesses 65 in the lower surface of the motor cylinder for locking the hammer motor and feed nut against rectilinear movement relative to each other. Between the portions 63 on the feed nut are projecting portions 66 on the motor cylinder fitting within the opening 42 in the tubular member and interlocking with the projections 63. In this form of the invention it will be understood that

the hammer motor can be disconnected from the feed screw without having to effect withdrawal of the feed screw from within a depending annular portion such as the portion 46 of the species of Figs. 1 to 10 inclusive; and no partial disassembly of the hammer motor is necessary to accomplish disassembly of the hammer motor from its guiding and supporting structure.

Assembling of the structure of Figs. 1 to 10 inclusive may easily be accomplished with the handle 41 and the member 28 removed. The nut 53 and washer 56 may be slid onto the feed screw; the separated rear head 8 of the motor can be put on over the feed screw, the feed nut threaded on the screw and gotten into the bore in the annular depending portion 46; the washer 56 and nut 53 may then be brought into the position of Fig. 6; the main portion of the hammer motor, on the guides 16, may be secured to the rear head 8; the parts may all be thrust forward as may be necessary; and the member 28 and the handle 41 be put and secured in their places. The mode of assembly of the modification of the invention will be clear from what has been said about the first species.

As a result of this invention it will be noted that an improved guiding and feeding means is provided for a drill hammer motor of the mounted drifter type. The improved guiding and feeding means provide an extremely compact structure with the parts of the feeding means which might be most readily injured shielded against possible damaging blows. It will further be noted that the parts may be easily assembled and provide an effective arrangement that is strong and durable. Rod type guides are provided in a rigid but simple construction and in the modification of the invention, particularly, disassembly is relatively simplified. Moreover, no danger of loosening of the connection of the feed nut to the hammer motor is possible with the constructions disclosed.

While there are in this application specifically described one form and a modification which the invention may assume in practice, it will be understood that these are shown for purposes of illustration and that the invention may be further modified and embodied in various other forms without departing from the spirit or the scope of the appended claims.

What we claim as new and desire to secure by Letters Patent is:

1. In a rock drilling mechanism, in combination, a rock drill, and feeding and supporting means for said drill comprising a central trunnion support, a tubular shaped member secured to said trunnion support and extending longitudinally of said drill, a feed screw arranged within and supported axially of said tubular shaped member, guiding and supporting means for said drill, and means for operatively connecting said rock drill to said feed screw including an annular shaped portion formed on said rock drill and fitting within said tubular shaped member, said annular portion slidably engaging the walls of said tubular member for guided movement longitudinally of the latter, a feed nut in operative engagement with said feed screw, and means for clamping said feed nut to said annular shaped portion.

2. In a rock drilling mechanism, in combination, a rock drill, a tubular shaped support member extending longitudinally of said drill, guide rods supported by said tubular shaped support member in positions parallel to the latter, guide

portions formed on said rock drill and slidably engaging said guide rods for guiding said rock drill for movement longitudinally of said tubular support member, a feed screw arranged within said tubular shaped member and extending parallel to a line parallel to the axis of the latter, and means operatively connecting said rock drill to said feed screw including a feed nut engaging said feed screw and held against movement relative to said rock drill.

3. In a rock drilling mechanism, in combination, a rock drill, a tubular shaped support member extending longitudinally of said drill, guide rods supported by said tubular shaped support member in positions parallel to the latter, guide portions formed on said rock drill and slidably engaging said guide rods for guiding said rock drill for movement longitudinally of said tubular support member, a feed screw rotatably supported within said tubular shaped member and extending parallel to a line parallel to the axis of the latter, means for operatively connecting said rock drill to said feed screw including a feed nut engaging said feed screw and held against movement relative to said rock drill, and means for rotating said feed screw to effect movement of said feed nut and rock drill therealong.

4. In a rock drilling mechanism, in combination, a rock drill, a tubular shaped support member extending longitudinally of said drill, guide rods supported by said tubular shaped support member in positions parallel to the latter, guide portions formed on said rock drill and slidably engaging said guide rods for guiding said rock drill for movement longitudinally of said tubular support member, a feed screw arranged within said tubular shaped member and extending parallel to a line parallel to the axis of the latter, an opening through said tubular shaped member and extending longitudinally thereof, and means for operatively connecting said rock drill to said feed screw including a portion formed on said rock drill and extending through said opening, a feed nut in engagement with said feed screw, and means for clamping said feed nut to the portion extending through said opening.

5. In a rock drilling mechanism, in combination, a rock drill, a tubular shaped support member extending longitudinally of said drill, guide rods supported by said tubular shaped support member in positions parallel to the latter, guide portions formed on said rock drill and slidably engaging said guide rods for guiding said rock drill longitudinally with respect to said tubular support member, a feed screw arranged within said tubular shaped member and extending parallel to a line parallel to the axis of the latter, an opening through said tubular shaped member and extending longitudinally thereof, a feed nut in operative engagement with said feed screw, and means for holding said feed nut against movement relative to said rock drill and including portions formed on said feed nut extending through said opening into engagement with said rock drill.

6. In combination, means forming a pair of parallel guides, a feed screw, means for mounting said feed screw for rotation on an axis extending parallel to said guides, a feed nut threadedly engaged with said feed screw, guiding means stationary with respect to said guides extending longitudinally of said feed screw, said feed nut slidably guided by said guiding means, a drilling motor supported by said parallel guides for movement along the latter, and operative connections

between said motor and feed nut holding the latter against movement relative to said motor and movable, upon feeding of said drilling motor, between said guiding means.

5 7. In combination, means forming a pair of parallel guides, a feed screw, means for mounting said feed screw for rotation on an axis extending parallel to said guides, a feed nut threadedly engaged with said feed screw, guiding means 10 stationary with respect to said guides extending longitudinally of said feed screw, said feed nut slidably guided by said guiding means, a drilling motor supported by said parallel guides for movement along the latter, and operative connections 15 between said motor and feed nut holding the latter against movement relative to said motor and movable, upon feeding of said drilling motor, between said guiding means and including interlocking connections carried in part by said motor and in part by said feed nut and disengageable 20 by relative movement between said motor and feed nut in a direction transverse to the axis of said nut.

8. In combination, a support, a slotted tubular member carried by said support, end members 25 carried by the opposite ends of said slotted tubular member, guide rods extending between said end members in parallelism with the axis of said slotted tubular member, a hammer motor supported on and guided by said guide rods, a feed screw extending longitudinally within said slotted tubular member, a feed nut on said feed screw movable longitudinally within said slotted tubular member and slidably guided by the latter, and operative connections between said nut and motor extending through the slot in said tubular member.

9. In combination, a support, a slotted tubular member carried by said support, end members 30 carried by the opposite ends of said slotted tubular member, guide rods extending between said end members in parallelism with the axis of said slotted tubular member, a hammer motor supported on and guided by said guide rods, a feed screw extending longitudinally within said slotted tubular member, a feed nut on said feed screw movable longitudinally within said slotted tubular member, and operative connections between 35 said nut and motor extending through the slot in said tubular member including portions on said nut projecting through said slot.

10. In combination, a support, a slotted tubular member carried by said support, end members 40 carried by the opposite ends of said slotted tubular member, guide rods extending between said end members in parallelism with the axis of said slotted tubular member, a hammer motor supported on and guided by said guide rods, a feed screw extending longitudinally within said slotted tubular member, a feed nut on said feed screw movable longitudinally within said slotted tubular member, and operative connections between 45 said nut and motor extending through the slot in said tubular member including a feed nut boss carried by said motor and guided within said tubular member.

11. In combination, a support, a slotted tubular member carried by said support, a drill motor 50 guided for movement longitudinally of said tubular member, means for guiding said drill motor including guide members supported by said tubular member and extending parallel to the axis of the latter, a feed screw extending longitudinally within said tubular member, a feed nut on said feed screw movable longitudinally within

said tubular member, and operative connections between said nut and motor including a portion formed on said motor projecting within the slot of said tubular member and having grooves therein extending transversely of said slot and projecting portions on said nut fitting within said grooves.

12. In a rock drilling mechanism, in combination, a rock drill, supporting and guiding means therefor along which the rock drill is movable during feeding and upon which the rock drill is supported during drilling, a feed screw extending longitudinally of said guiding means, a feed nut supported by said guiding means for guided movement therewith, and detachable connections between said rock drill and said feed nut including at least one transverse projection on one of the same and a transverse opening in the other for receiving said projection.

13. In a rock drill, in combination, a drill steel actuator, and feeding and supporting means for said actuator including a tubular shaped member extending lengthwise of the drill, a feed screw arranged within and supported axially of said tubular shaped member, said supporting means providing a longitudinal guideway substantially coextensive with said member and along which said actuator is guided for movement, a feed nut threadedly engaging said feed screw, said feed nut fitting within and conforming in shape to and having sliding engagement with the inside walls of said tubular shaped member and supported by the latter independently of said actuator, and operative connections between said feed nut and said actuator.

14. In a rock drill, in combination, a drill steel actuator, supporting and guiding means for said actuator including a cylindric hollow member and providing a guideway for said actuator extending substantially coextensively with said hollow member, said hollow member having a narrow opening extending longitudinally along one side thereof, feeding means for said actuator including a feed screw extending centrally within said hollow member and a feed nut threadedly engaging said screw and arranged within and slidably engaging the inside walls of said hollow member substantially throughout the circumferential extent thereof, said feed nut being

supported by said hollow member independently of said actuator, and operative connections between said feed nut and said actuator including a connecting portion extending through said narrow opening.

15. In a rock drill, in combination, a drill steel actuator, supporting and guiding means for said actuator along which the latter is guided during the drilling operation, feeding means for said actuator including a feed screw extending longitudinally of said supporting and guiding means and a feed nut threadedly engaging said screw and guided for movement along said guiding means with said actuator, said feed nut being supported by said guiding means independently of said actuator, and an operative detachable connection between said actuator and said feed nut, said connection connecting said actuator for guided movement with said feed nut and freely detachable from said nut in a direction at right angles to the path of movement of said feed nut.

16. In a rock drill, the combination comprising a guide, a drill steel actuator movable along said guide, and means for effecting feed of said drill steel actuator along said guide comprising a feed screw extending longitudinally of and journaled on said guide, a feed nut threadedly engaging said feed screw and guided for movement along said guide concurrently with said drill steel actuator, and a detachable interengaging connection between said actuator and said feed nut, said connection interengaging said feed nut and said actuator for connecting the same together for guided movement and freely releasable upon relative lateral movement between said actuator and said nut.

17. In a rock drill, the combination comprising a guide, a drill steel actuator movable along said guide, and feeding means for said actuator comprising a feed screw extending lengthwise of and journaled on said guide, a feed nut guided on said guide wholly without support by said actuator, and a laterally releasable, interengaging connection between said feed nut and said actuator whereby the latter may be released from said feed nut while said nut remains in guided relation with said guide.
